UNITED STATES PATENT OFFICE.

THOMAS H. SPARKS, OF WICHITA, KANSAS.

SPRING APPARATUS FOR VEHICLES.

1,150,714.

Specification of Letters Patent. Patented Aug. 17, 1915.

Application filed January 6, 1915. Serial No. 887.

To all whom it may concern:

Be it known that I, THOMAS H. SPARKS, a citizen of the United States, residing at Wichita, in the county of Sedgwick and State of Kansas, have invented certain new and useful Improvements in Spring Apparatus for Vehicles; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in springs for bodies of vehicles and the object in view is to produce a simple and efficient apparatus of this nature so arranged as to take up vibrations incident to the movements of the body in different directions.

My invention comprises various details of construction, combinations and arrangements of parts which will be hereinafter fully described, shown in the accompanying drawings and then specifically defined in the appended claims.

I illustrate my invention in the accompanying drawings, in which:

Figure 1 is a side elevation of the rear portion of the vehicle showing the application of my springs thereto. Fig. 2 is a sectional view on line 2—2 of Fig. 1, looking in the direction of the arrow, and Fig. 3 is a sectional view on line 3—3 of Fig. 2.

Reference now being had to the details of the drawings by letter, A designates the rear axle of the vehicle, mounted in a cylindrical shell A', and B is a hub plate fixed thereto having ears C projecting from the face thereof and spaced apart, as shown clearly in Fig. 3 of the drawings, and which are apertured for the reception of the bolts D.

E designates the body of the vehicle mounted upon the frame E' and to which latter the ends of the semi-elliptical springs E³ are connected by means of the links E² and E⁴, as shown in Fig. 1 of the drawings. Said springs E³ pass underneath the axle A but are not connected therewith. Other springs, designated by letter H, of similar construction are fastened at their upper ends to the inner ends of the coiled springs I, the outer ends of the latter being connected

to a plate I' secured to the side of the body. Said springs H are curved as shown in Fig. 2 of the drawings and extend underneath the bolt L which passes through registering apertures in the plate I', which latter is apertured for the reception of a second bolt L² which passes through eyes in a clamping plate L³ secured to the spring E³ by means of a nut L⁴. It will be noted that the spring E³ is supported by the two springs H and is free from attachment to the shell A' about the axle.

By the provision of springs made in accordance with my invention, it will be noted that the body of the vehicle, mounted as shown and described, may have a yielding movement laterally as well as rearwardly, the end springs being supported upon a side spring, thereby distributing the weight and tending to make the springs more sensitive to absorbing vibration.

What I claim to be new is:—

1. A spring apparatus for vehicles comprising, in combination with the body and axle of a vehicle and frame upon which the body is mounted, a shell upon the axle, a hub plate secured to the shell, a spring secured at one end to the hub plate and a coiled spring connecting its other end with the body, a side spring secured at its ends to said frame and fastened to the spring which is connected to the hub plate and positioned underneath the axle.

2. A spring apparatus for vehicles comprising, in combination with the body and axle of a vehicle and frame upon which the body is mounted, a shell upon the axle, a hub plate secured to the shell and provided with ears, a side spring connecting its ends to the frame and passing underneath the axle, a spring secured at one end to said ears and a coiled spring connecting its other end with the body, and connections between the side spring and said spring which is connected to the hub plate.

3. A spring apparatus for vehicles comprising, in combination with the body and axle of a vehicle and frame upon which the body is mounted, a shell upon the axle, a hub plate secured to the shell and provided with ears, apertured lugs projecting from said plate in pairs upon either side of the shell, curved springs pivotally connected at their outer ends to said lugs, coiled springs connecting their other ends with the body of the vehicle, a side spring connected at its

ends to the frame and projecting underneath the rear axle and connections between said side spring and the curved spring.

4. A spring apparatus for vehicles comprising, in combination with the body and axle of a vehicle and frame upon which the body is mounted, a shell upon the axle, a hub plate secured to the shell and provided with ears, apertured lugs projecting from said plate in pairs upon either side of the shell, curved springs pivotally connected at their outer ends to said lugs, coiled

springs connecting their other ends with the body of the vehicle, a side spring connected at its ends to the frame and projecting underneath the rear axle, and clamping means for connecting the side springs with said springs which are connected to the lugs. 15

In testimony whereof I hereunto affix my signature in presence of two witnesses.

THOMAS H. SPARKS.

Witnesses:

Mrs. J. F. BOLTON,
O. G. FARLEY.
